UNITED STATES PATENT OFFICE.

FANNIE L. MATSON, OF SAN JOSÉ, CALIFORNIA.

FRAME FOR READING AND NUMBER CARDS.

SPECIFICATION forming part of Letters Patent No. 371,338, dated October 11, 1887.

Application filed June 4, 1887. Serial No. 240,333. (No model.)

To all whom it may concern:

Be it known that I, FANNIE L. MATSON, of San José, county of Santa Clara, State of California, have invented an Improvement in 5 Reading, Language, and Number Frames; and I hereby declare the following to be a full, clear, and exact description of the same.

My invention relates to a device, which I call a "reading, language, and number frame."

10 It consists of jointed or hinged standards, with detached bases, having upon one side of the standard a board with grooves or channels for the reception of different cards, upon the opposite side a combined desk and holder, 15 while at the upper end is a revolving board or frame having oblique and straight grooves made in it for holding cards and exposing them in different positions.

20 Referring to the accompanying drawing for a more complete explanation of my device, the figure is a perspective view of my device.

25 A are two posts or standards, which are mortised or fitted into the feet or supports B, so that they may be removed or replaced at any time, being held there by means of hooks C. The upper portion of the standard is also hinged to the lower portion, and the two are held together by hooks, as shown at D. Upon one 30 side of these standards is fixed a board or surface, E, having the grooved or channeled strips F placed at certain distances apart, so as to receive and hold cards which it may be desired to place in these grooves, either singly or so as to form sentences or combination of 35 words, letters, or figures, or any primary work.

The lower portion of the board E is secured to the lower portion of the standard A by means of hooks G, so that when the frame is to be folded up into a smaller compass this 40 section may be removed, thus allowing the parts to be folded together. Upon the opposite side of the standards from the boards E is fixed a vertical shallow case, H, having a series of compartments, in which the different 45 cards may be placed when not in use, and, as this case is adjacent to the channeled or grooved boards, it is convenient to change the cards as may be desired. This case is closed up by the hinged lid I, which is held by the jointed sup- 50 porting-links J, so that when opened out it forms a desk for writing or other work. Be-

ing closed up, it forms a cover to close the case H.

Upon the upper part of the apparatus is a board, K, which extends between the two standards A, and is suspended upon central pivot-pins, L, so that it may be turned vertically, horizontally, or reversed, as may be desired. In the face of this board are numerous narrow channels, M, of sufficient depth and width to receive the edges of the cards which are used. These channels are made either at an oblique angle with the face of the board or are made directly in at right angles with the face, each alternate channel being oblique and the others rectangular. By this construction the board may be turned so as to stand horizontally, and a line of cards may be set up in the rectangular channels, so as to stand at right angles with the face of the board and in view of the scholars sitting in front of the stand, and rows of cards which may be behind the first ones will be concealed until these first ones are removed. If, however, it is desired to have the cards exposed in series, the board is turned so as to stand obliquely, and the cards being set in the oblique grooves or channels those behind and above can be seen as well as those in front and below. This enables me to combine the words, letters, or figures in any suitable or desirable manner.

Upon the sides of the standards A are fixed guides, within which are the rods N, these rods having hooks O at the top for the purpose of receiving the rings or loops of charts or maps, 80 so that the latter may be suspended therefrom, and by sliding the rods or bars N up or down they will be fitted to any size of chart or map that it may be desired to expose.

The rods are held at the proper point by 90 pins passing through holes in their lower ends and into corresponding holes in the sides of the standards, or by other suitable means.

The whole device forms a convenient arrangement for use in schools and in similar 95 places for object-teaching, sight-reading, number-work, &c.

Having thus described my invention, what I claim as new, and desire to secure by Letters Patent, is—

1. A frame consisting of the standard A, hinged so as to fold, and the supporting-feet

B, into which the standards are mortised, in combination with the hooks, whereby the parts are attached together so that they may be easily separated at will, substantially as described.

2. The stand comprising the centrally-hinged folding standards, and feet to which they are removably attached, in combination with the boards extending from one standard to the other, having the projecting cleats forming grooves or channels for the reception of cards, the lower section being movable and secured by hooks, substantially as described.

3. The hinged folding standards and removable feet and the grooved or channeled boards or surfaces, in combination with the rack or desk fixed to the opposite sides of the standards, substantially as described.

4. The folding standards with the removable feet, grooved or channeled face-board upon one side, and the card-holding rack upon the back, the door of which forms a desk when opened, substantially as described.

5. The standards having the pivoted revolving board supported between them, said board having its surface slotted alternately with obliquely-cut and rectangular grooves or channels to receive the edges of the cards and support them with relation to the angle or position of the board, substantially as described.

6. The pivoted revolving board having its faces channelled with alternate rectangular and obliquely-cut slots for the reception of cards, so that the latter may be exposed or concealed by the position of the board, in combination with the vertical standards between which the ends of the boards are pivoted, and the card-holding case or rack beneath the board and adjacent thereto, substantially as described. 35

7. The vertical folding standards with the stationary and pivoted grooved or channelled boards and card-rack, in combination with the sliding rods adjustable upon the sides of the standard, and having supporting hooks for charts at the upper end, substantially as described. 40 45

8. A frame comprising the folding standards and removable feet, the card-rack and desk upon one side of the standard, and the grooved or channeled surface upon the opposite side, together with the pivoting revolving board at the top, and the adjustable chart or map supporting rods, substantially as described. 50

In witness whereof I hereunto set my hand. 55
